UNITED STATES PATENT OFFICE.

CHESTER L. AMES, OF PHOENIX, ARIZONA.

BOOKRACK.

Application filed March 11, 1928. Serial No. 93,908.

This invention relates to book racks, and particularly to book racks of that character wherein adjustable end members are employed.

5 The primary object of the invention is to provide a book rack or stand having an adjustable end plate or piece of such character that the weight of the book rack base and articles placed thereon is utilized to firmly 10 maintain the end plate in its desired position of adjustment, whereby to more firmly hold books in proper position upon the rack. A further object is to provide a book rack of such character that adjustment of the movable 15 end plate may be readily made, and wherein the same automatically locks itself in adjusted position immediately it has been released.

A still further object is to provide a book 20 rack of extremely simple construction, which may be manufactured and marketed at low cost, which involves simplified processes in its construction, which will prove durable and at all times effective and operative when 25 in use, and which will prove highly practical for the purposes for which it is intended.

With these objects in view, together with others which will appear as the description 30 proceeds, the invention consists in the novel construction, combination and arrangement of parts, all as will be described more fully hereinafter, illustrated in the drawings, and particularly pointed out in the claims.

35 Fig. 1 is a side elevation of a book rack or shelf embodying the invention,

Fig. 2 is a top plan view of the improved shelf,

Fig. 3 is an end view of the shelf,

40 Fig. 4 is a perspective view of a book shelf illustrating a slight modification, and

Fig. 5 is a detail fragmentary sectional view taken through the shelf base and end plate and illustrating more particularly the 45 operation of the device as shown in Fig. 4.

Referring now more particularly to the drawings, the improved book rack includes a shelf or base represented at 6, of any desired length and breadth and formed of any 50 suitable material. This shelf or base is supported at one end in slightly raised position by a fixed end piece 7, the lower portion of the latter constituting a leg to rest upon a table or other article of furniture.

55 The adjustable end piece includes a plate represented at 8, which normally rests on its

lower edge upon the upper surface of the base or shelf 6, and which terminates at its upper end preferably in the same plane with the corresponding end of the fixed member 7. 60

The inventive characteristics reside in the construction and assemblage of the adjustable plate or end piece 8, and in carrying forth this idea legs indicated at 9 are employed. These legs depend from the plate 8 65 and when in normal position maintain the plate in locked position against movement longitudinally of the shelf 6, and also maintain the latter in true horizontal position. These legs, therefore, have their lower portions offset or out of the vertical plane of the plate 8, and project in the direction of the fixed end 7. The lower surfaces of the legs are rounded as indicated to form rockers, and the normal point of bearing of these 75 rockers is represented at 10. The legs are associated with the plate in such manner that when resting upon their normal points of bearing 10, the plate will be at the desired angle with respect to the base 6. It has 80 been found most practicable to normally position the plate 8 at right angles to the base 6, however, it will be understood that the degree of the angle may be varied if desired. The legs 10 are provided with stops 11 85 disposed directly above the normal points of bearing of the legs 10 and engage with the under face of the shelf 6 when the legs are resting upon their normal points of bearing.

With the end plate and its legs and stops 90 arranged in this manner, the weight of the shelf 6 and any books that may be positioned thereon is utilized to maintain the plate against adjustment. The stops or pins 11 95 operate as fulcrums, and the outer edge 12 95 of the shelf 8 will be caused to firmly bind with the upper surface of the base 6. When it is desired to adjust the plate, the base may be slightly lifted so as to allow the plate 8 to be slightly inclined in the direction of the 100 fixed end member 7, whereupon the adjustable plate may be freely moved either inwardly or outwardly, of the base. When the desired adjustment has been made, the weight of the base and the books thereon, 105 operating through the fulcrum 11, will cause the plate 8 to swing outwardly until the edge 12 is brought into contact with the shelf 6. When so positioned, the end piece will be perpendicular to the base 6 and locked 110 against movement.

In one embodiment of the device, the in-

vention is carried out by providing the base 6 with spaced parallel longitudinally disposed slots 13, through which the rocker legs 9 project, and each leg, at the proper place, 5 is provided with a pin 11 for the purposes above set forth.

In Figs. 4 and 5, the same inventive idea is carried out, except that the slots in the base 6 are dispensed with. In this instance, 10 the adjustable end plate 8 is provided at its extremities with legs 9 straddling the base 6. The forward ends of these legs are connected by a cross member 14, which not only operates as an effective stop, but also lends rigidity to the leg structure.

It is obvious that when constructed in the manner set forth, the book shelf will effectively operate to accomplish the several objects set forth, and while the present is a description of the invention in its preferred embodiments, it is to be understood that variations in the construction of parts and assemblage thereof may be resorted to if desired without departing from the spirit of 25 the invention as defined by the claims.

Having thus described my invention, I claim:

1. In a device of the class described, a base, a plate resting at its lower edge upon said 30 base, a rocker leg depending from said plate and having its normal point of bearing disposed beyond the lower edge of the plate, and a stop on said leg disposed in the same vertical plane with the said point of bearing.
2. In a device of the class described, a base, a plate resting at its lower edge upon said 35 base, a rocker leg depending from said plate

and having its normal point of bearing beyond the plane of the plate when the latter is perpendicular to the base, and a stop on 40 said leg engaging with the under face of said base when the rocker is resting upon its normal bearing point.

3. In a device of the class described, a base, a plate resting at its lower edge upon 45 said base, a pair of rocker legs depending in spaced relation from said plate and having their normal points of bearing out of the vertical plane of said plate, and means on said legs limiting rocking movement of the latter 50 in one direction when the plate has assumed a predetermined angle relative to said base.

4. In a device of the class described, a base having spaced longitudinal slots therein, a plate, a pair of rocker legs carried 55 by said plate and extending down through said slots, the normal load sustaining points of said rockers being out of the vertical plane of said plate, and stops on said rockers engageable with said base when the plate is 60 perpendicular thereto.

5. In a device of the class described, a base, a plate adapted to rest at its lower edge upon said base, a rocker leg depending from said plate and having a bearing portion disposed out of the plane of the latter, a stop on 65 said leg disposed in the plane of said bearing portion, and said stop so spaced from the plate as to be engaged with the lower face of the base when the plate is resting upon 70 and perpendicular to the base.

In testimony whereof I affix my signature.

C. L. AMES.
